UNITED STATES PATENT OFFICE.

LINNAEUS E. BAKER, OF FORT WAYNE, INDIANA, ASSIGNOR TO WAYNE OIL TANK AND PUMP COMPANY, OF FORT WAYNE, INDIANA, A CORPORATION OF INDIANA.

AUTOMATIC DRAIN-BACK FOR ELEVATED LIQUID-CONTAINERS.

1,395,890.

Specification of Letters Patent.

Patented Nov. 1, 1921.

Application filed December 16, 1919. Serial No. 345,416.

To all whom it may concern:

Be it known that I, LINNAEUS E. BAKER, a citizen of the United States, residing at Fort Wayne, in the county of Allen and State of Indiana, have invented new and useful Improvements in Automatic Drain-Backs for Elevated Liquid-Containers, of which the following is a specification.

My invention is an automatic drain-back for elevated liquid containers, and provides means for draining such containers whenever the apparatus is in out of use or, as it is called, locked up position.

In handling inflammable liquids such as gasoline with dispensing apparatus having an elevated container, safety regulations require that such liquid be drained back to the underground storage tank or other source of supply when the apparatus is locked up, as 20 for the night. My invention provides an automatic drain-back to meet such requirements.

The particular embodiment of my invention selected for illustration is a gasolene dispensing apparatus for out-door use.

The drawing shows an elevation of an elevated container for liquid, with parts broken away and in section to show the automatic drain-back mechanism in position 30 to operate and the means for operating same. Parts below the elevated container are shown in dotted lines.

Referring now to the drawings; A, is the cylinder of an elevated container usually 35 made of glass or provided with windows; a, is the container bottom and a¹, is the top, these parts being suitably connected by tie-rods a². The container is mounted upon a pedestal P.

B, is the discharge pipe vertically slidable 40 through the stuffing box a³.

C, is the fill pipe and D, the overflow pipe fixed in position within the container.

A drain-back orifice E, is provided in the 45 bottom of the container to carry back to the storage tank the contents of the container when so desired, as when locking up the apparatus for the night. A needle valve e, guided by the bracket e¹, is adapted to keep 50 the orifice E, normally closed and to be raised to open position by manipulation of the lever e², being pivoted thereto by a screw e³, provided to adjust the length of the needle valve element. The lever e², is pivoted

at e⁴, to a bracket a⁴, on the container top 55 a¹. The free end e⁵, of the lever e², is adapted to contact with and be raised by the top of the discharge pipe B, when raised to drain back position. Obviously the lever e², may be operated in any other convenient 60 manner.

The vertically slidable discharge pipe B, carries on its lower end an L b, terminates outwardly in a hose connection b¹, and carries a setting latch L, with latch bar l, 65 adapted to engage suitable notches in the scale S. When the discharge pipe is raised to the extreme position shown in the drawing, that is to "lock" position, it is ready to be left for the night and will then automatically drain the elevated container in the manner shown in the drawing.

When the latch bar l, is withdrawn from the lock position and lowered, the attached discharge pipe permits the lever e², and the 70 needle valve e, to descend by gravity and close the orifice E, before the "fill" position is reached by the latch bar. The elevated container may then be refilled.

Any means for causing the drain-back 80 valve to be automatically opened by a vertically adjustable member when the apparatus is in lock up position is within the scope of my invention.

I claim as my invention and desire to secure by Letters Patent of the United States.

1. In a liquid dispensing apparatus having an elevated liquid container, the combination of a valve to drain the contents of the container back to the storage tank, a 90 moving element within the container, and means connected with the valve and engageable by the moving element, to open the valve when placing the apparatus in position for temporary disuse. 95

2. In combination with a drain valve and an adjustable discharge pipe for the elevated liquid container of a dispensing apparatus, means for opening said valve automatically through contact with the discharge pipe when the apparatus is put in lock up position. 100

3. In a liquid dispensing apparatus having an elevated liquid container, the combination of a drain valve for the elevated liquid container, a vertically slidable discharge pipe, and a lever to automatically open said valve by the contact of said lever 105

with the discharge pipe when the apparatus is manipulated to lock up position.

4. In a liquid dispensing apparatus having an elevated container, the combination of a vertically movable discharge pipe, a drain valve normally resting upon its seat in closed position; a lever connected to said valve, said lever projecting into the path of the discharge pipe to raise the valve from

its seat upon a predetermined movement of the discharge pipe.

In testimony whereof I have hereunto set my hand in presence of two subscribing witnesses.

LINNAEUS E. BAKER.
